UNITED STATES PATENT OFFICE.

NORMAN ENHOLM, OF CHAPPAQUA, NEW YORK.

OIL BURNER.

Application filed January 21, 1925. Serial No. 3,881.

This invention relates to an oil burner for mixing air and oil vapor to produce a combustible or explosive mixture and particularly to the mixing of air with the vapors of petroleum oils such as kerosene. The object of the invention is to provide an oil burner which will vaporize the oil and mix it with the air in continuous quiet and efficient manner and without the use of high pressures or small nozzles.

Further objects and advantages of the invention will appear from the following description taken in connection with the accompanying drawings in which

Fig. 1 is an elevational view of apparatus illustrating one embodiment of the invention with parts broken away and in section.

Fig. 2 is a section on line A—A of Fig. 1.

Fig. 3 is a view similar to Fig. 1 but illustrating a modification, and

Fig. 4 is a diagram showing a current supply and charging system for the electrically driven motor.

In the embodiment of the apparatus shown in Figs. 1 and 2 a burner embodying this invention comprises a curved pipe 1 into which oil vapor passes from chamber 2 having vaporizing plate 3. In pipe 1 the oil vapor is mixed with air passing in the direction of the arrow and forced along as by fan 4 driven by motor 5. The outlet 1^a of the pipe is positioned under the vaporizer 2, 3 and a portion of the pipe 1 so that the burning oil vaporizes the inflowing oil and preheats the mixture of oil vapor and air.

The inflow of oil preferably is adjustable as by sliding valve 6 connected to oil pump 7 in float chamber 17 by pipe 8 and to the vaporizer 2, 3 by pipe 11 from which it flows onto the plate 3. A gravity overflow pipe 12 returns any excess oil back to the reservoir float chamber 17 so that only vaporized oil can enter the pipe 1 and be burned at gauze 9 in the outlet 1^a.

The supply of oil to float chamber 17 enters through inlet 10 and is controlled by float 16 in usual manner and the pump 7 may be driven by motor 5 through gears in casing 14 driving the vertical pump shaft 14'.

The supply of air enters through windows 23 controlled by the shutter ring 13 which may be connected to the oil control valve 6 by arm 24 and link 15 so that the oil and

air supply will be adjusted together to aid in maintaining the desired proportions in the mixture to be burned.

To ignite the burner the motor 5 will be started and a preliminary heating provided by burning oil in the saturated asbestos ring 18, which will vaporize oil in vaporizer 2, 3 and ignite the mixture into a flame above the gauze 9 to form the flame.

In the burning of oil according to this invention a mixture of oil vapor and air feeds the flame. In forming the mixture heated oil vapor is supplied to the stream of air and further heat may be supplied to maintain a high temperature of the mixture but preferably below the ignition point so that combustion will not take place until the mixture passes the gauze 9. The flame itself is then utilized to supply further vapor to the air stream and so the process is continuous. There is no burning of the oil as liquid or unmixed vapor and there is no clogging of passages and no excessive pressure is needed to supply the flame. By this burning of the mixed gases the formation of soot and other deposits is avoided and combustion is carried on in a clean, efficient and noiseless manner.

The mixture of oil vapor and air produced by this invention may also be used as an explosive mixture, for instance in internal combustion engines. In such case the suction of the intake manifold of the engine may be used to draw in the current of air as illustrated in Fig. 3 where the pipe 1' connected at one end to the intake manifold and at the other end has air inlet windows 23' controlled by the shutter ring 13'. At an intermediate point the pipe 1' is provided with the oil vaporizer 2', 3' supplied with oil by pipe 11' and drained by overflow pipe 12'. The vaporizer 2', 3' may be heated by any suitable means as by the engine exhaust or by an oil burner as shown in Figs. 1 and 2. In the latter case the pipes 11 and 11', 12 and 12' and shutter rings 13 and 13' may be connected for simultaneous control so that the greater the throttle opening at 23' the larger will be the burner flame.

To provide electric current to the motor, in event of interruption which usually occurs on service lines, I have shown in Fig. 4 the main line 27, switch at 28 when closed connects through wires 29 and 30

with charger 31. Positive output 32 of charger 31 leads to wire 33 thence through switch 28 and to motor 5 then to relay 34 and back to charger 31. Secondary winding 35 of relay 36 is shunted across battery 37.

Assuming battery 37 is below normal charge current from charger 31 will pass to contact 38 said contact being closed due to 10 tension of spring 39, through primary winding 40, to battery 37 to relay 34 and back to charger 31.

As the battery 37 becomes more fully charged the current flowing through primary coil 40 decreases while that in secondary coil 35 increases until spring 39 is overcome and contact 38 is opened thereby guarding against over charging of the battery 37.

In case of failure of current coming from 20 the main line 27 relay 34 becomes demagnetized and spring 41 closes contact 42. Current from battery 37 flows through contact 42 to wire 33 to switch 28 then to motor 5 and back to battery 37.

When service 27 is resumed relay 34 opens contact 42 and "cuts out" battery 37 and current for the operation of the motor 5 and charging of the battery 37 is taken through the charger 31 from the main line 27 as 30 above described.

The principle of this invention is not confined to the apparatus shown and described but it is intended to cover such modifications

thereof as fall within the scope of the appended claims.

35

I claim:

1. An oil burner comprising an air supply pipe, an oil vaporizer connected thereto, and an oil supply pipe and an oil overflow pipe connected to said vaporizer, and means for 40 heating said vaporizer comprising an extension of said air supply pipe adapted to pass the mixture of air and gas to a flame forming means beneath said vaporizer.

2. An oil burner comprising an air supply 45 pipe, an oil vaporizer connected thereto and an oil supply pipe and an oil overflow pipe connected to said vaporizer, means for heating said vaporizer comprising an extension of said air supply pipe adapted to pass the 50 mixture of air and gas to a flame forming means beneath said vaporizer, and means for starting said burner comprising oil retainer means in proximity to said flame forming means.

3. In an apparatus for mixing air with oil vapor or gas, the combination with an air passage of a vaporizer connected thereto, means for heating said vaporizer, and means for supplying oil to said vaporizer comprising a float chamber, means for conveying oil from said float chamber to said vaporizer, and means for carrying off any excess oil from said vaporizer back to said float chamber.

60 NORMAN ENHOLM.
